LIFT TRUCK

George Bevan, Norfolk, Va., assignor to Freight Handling Corporation, a corporation of Virginia

Application May 12, 1947, Serial No. 747,361

4 Claims. (Cl. 214—113)

1

The present invention relates to lift trucks and particularly to mobile trucks of the so called "fork lift" type in which the platform upon which the load to be transported is placed has a fork-like appearance owing to the fact that it comprises a plurality of elongated parallel members extending horizontally from a supporting base, these members generally tapering outwardly from the base and thus resembling tines.

Many lift trucks of this type are now in use for the transportation of goods through relatively short distances, particularly from place to place within a factory building, for movement of freight from factories into freight cars or from freight cars into warehouses, and elsewhere. The loads which these trucks are called upon to handle vary greatly in character. Raw materials in bales and materials in self-supporting containers, such as wooden boxes, must, of course, be frequently and likewise granular and pulverulent materials in paper or cloth sacks, these envelopes being non-self-supporting and being readily broken or torn. Thus the truck must be of such character as to have the capacity to receive, safely transport, and deliver sacks of flour as well as containers which will not break even when subjected to rough handling.

Certain commodities may be placed, for the purpose of transportation and ultimate delivery, directly upon the tines or elongated load supporting elements of the conventional fork lift truck. Hogsheads of tobacco and large bales and boxes of other goods may with advantage be handled in this manner. Other commodities, such for instance as sacks of granular or pulverulent material, may be transported with greater safety upon continuous flat platforms which provide uniform support. To provide such supporting surfaces it has therefore been conventional practice for those employing lift trucks in the transportation of goods in sacks or bags to employ what are known as "pallets." A pallet comprises a load supporting floor adapted to receive, for instance, from three to six flour sacks forming a bottom layer, with others piled thereon in layer formation to form a stack of from fifteen to thirty such sacks, together with means to space this load carrying floor a short distance from the ground. This spacing of the pallet floor permits the tines of a fork lift truck to be moved into position under the pallet floor so that the pallet may be engaged, raised, and transported, together with its superposed load. The pallet, at the point of load discharge, is generally lowered by the fork lift onto a supporting sur-

2

face, still carrying its load, or deposited upon a previously placed load, and may be lost to its owner, particularly if goods in sacks or bags are being loaded into a freight car for transportation to a distant point. To prevent loss of pallets in this manner it has been proposed that the lift truck be provided with a pusher by means of which a load may be held stationary as the truck is retracted and that the pallet and lift truck be provided with mutually interlocking means to insure that the pallet will not be separated from the lift truck but will simply be withdrawn from beneath the load.

In accordance with the present invention a load supporting pallet of novel character is provided, this being substituted for the usual pallet having spaced upper and lower floors. Improved means are provided for detachably securing this pallet to the load carrying portion of a fork type lift truck. As a feature of this part of my invention, the means for securing the pallet to the fork truck are preferably formed so that they are actuated into and out of securing relation merely through manipulation of the truck bodily relatively to the pallet.

As a further feature of my invention the load supporting pallet takes the form of a steel plate of desired configuration, and this steel plate may have legs or casters thereunder whereby one edge may be supported several inches above a floor while the other edge is against the floor. Thus, this pallet if placed upon a horizontal surface will assume an inclined position unless that edge which is normally against the surface is supported upon blocks or by other members. It is the function of the legs or casters to support one edge of the pallet at such a height that the usual forks of a lift truck may readily be inserted beneath the pallet and to permit that manipulation between the truck and pallet required to engage and disengage the truck and pallet.

As previously stated, the improved load supporting pallet is to be permanently retained at one location and, is preferably held against discharge with its load when the pusher of the associated truck is operated to hold a pile of goods, against movement while the supporting pallet is being withdrawn from beneath the pile. For that reason a special means is provided for detachably securing the pallet to the elevating platform or forks of the truck. This means permits the pallet to be readily secured in operative position and to be as readily detached, while at the same time is of such character as to require

no modification or alteration in the structure of the truck itself, which is important. Thus I prefer to secure detachable the pallet in position to rest upon the forks so that the weight of the pallet and its load is transmitted to the forks in the usual manner and I provide, as a securing means, one or more members that may be designated "attachment members," extending between the elevating platform of the truck and the pallet. By providing means such as described that may be readily added to a lift truck not intended for such operation, the operator of a lift truck can convert the truck quickly and easily, and without the use of securing bolts, or without modifying the structure of the truck in any way, for the transportation of goods of widely different characteristics. It will be appreciated by one skilled in the art that, without departure from the invention, various types of devices for detachably connecting the continuous surface type of load carrying platform to the lift truck may be devised, although that form to which brief reference has been made, and which will hereinafter be described in detail, is preferred.

The improved pallet is preferably fabricated of metal and may be quite thin, whereas the conventional pallet has a thickness of five or six inches. When a conventional pallet of five or six inches in thickness is withdrawn from beneath a pile of goods, such goods necessarily drop this distance of five or six inches onto a supporting floor, or onto a pile which has been previously deposited, causing bags to burst as they pass over the edge of the pallet and also causing the bags or cartons to lose pile formation. When my improved skid is employed no such drop occurs upon discharge of goods and all breakage and loss of pile formation is avoided.

The novel pallet furthermore makes possible the practice of an improved method which results in the realization of substantial economies in the loading and transportation of goods. It also becomes possible to fully load freight cars without additional labor. The use of large numbers of pallets is avoided, the improvement making it possible to transfer a given quantity of goods by means of a lift truck and several pallets, and with the expenditure of a relatively small amount of manual labor whereas, when conventional pallets are employed, a substantial number are required and the amount of labor required substantially increased. Numerous other advantages will be apparent.

In the accompanying drawings:

Figure 1 is a perspective view of the forward portion of a lift truck of the fork type, showing the novel pallet in chain lines and the elements for detachably connecting this pallet to the truck in full lines;

Figure 2 is a section on line 2-2 of Figure 1;

Figure 3 is a section on line 3-3 of Figure 1;

Figure 4 is a perspective view of one of the attachment elements;

Figure 5 is a similar view of a modified form of attachment element;

Figure 6 is a partial section taken on line 6-6 of Figure 2;

Figure 7 is a section on line 7-7 of Figure 6;

Figure 8 is a perspective view of a portion of the underside of my pallet, showing an attached hook member which forms a portion of the means for separably connecting this pallet to the truck;

Figure 9 shows in side elevation one of the elongated tines of the fork lift, showing also, in process of assembly therewith, one of the mem-

bers by means of which the separable connection of the pallet to the truck may be effected;

Figure 10 is a section on line 10-10 of Figure 9;

Figure 11 shows in side elevation a pallet resting with one end on a floor or base while the other end is supported by wood blocks, a portion of the front end of a conventional fork lift truck being illustrated, with the tines of the fork under the platform;

Figure 12 is a view showing the elevating platform of the truck in a higher position, the load carried by the platform being supported directly above a similar load and ready to be discharged; and

Figure 13 is a view of the parts of Fig. 12 with the pusher of the truck, actuated and the truck with its attached pallet simultaneously retracted to effect the discharge of the load from the pallet upon the top of a previously deposited load.

As previously explained, the invention is primarily concerned with trucks of the fork lift type. Such trucks are well known and are in common use and, inasmuch as the details of construction of the truck itself are unimportant insofar as the present invention is concerned, these details are not illustrated and will not be described.

In the rather diagrammatic Figures 11, 12 and 13 a portion of the truck frame is indicated at F, one of the front wheels at W, the mast at M, carriage at C, with its associated load carrying fork F and load pushing or discharging mechanism comprising pusher frame P and hydraulic pusher frame actuating mechanism H. The mast M is provided, adjacent its lower end, with attached hook members one of which is indicated at 10, these members engaging and being supported by a horizontally extending rod 11 carried by the truck frame. The mast may be rocked about rod 11 through a limited angle, either forwardly from the vertical position in which it is shown in Figure 11 to an inclined position such as that of Figure 12, or rearwardly through a small angle, as desired, and held in any such position to which it may be moved, by any suitable mechanism. The carriage C is supported for movement vertically along the mast and some suitable means for accomplishing this will be utilized. One mechanism for effecting tilting of the mast and vertical reciprocation of the carriage C is, for instance, shown in Patent 2,299,445 issued to E. W. Weaver. Any other such means may, however, be employed, the details being immaterial insofar as the present invention is concerned.

The means H for advancing and retracting the pusher frame P may consist principally of two cylinders 12, secured to opposite sides of the carriage C respectively, each having a spring retracted telescopic piston 13 upon the outer ends of which the pusher frame P is mounted. A conduit for conducting fluid under pressure to the cylinder shown is indicated at 14 and it will be understood that by the use of known devices the operator may control the flow of fluid under pressure to and away from the cylinder and hence the operation of the hydraulic means H and the movements of the pusher frame P.

The forks or tines 15 selected for illustration include two or more (in this case four) generally parallel horizontally extending outwardly tapering elements, the heavier ends of these elements being suitably attached in a rigid manner to the carriage or elevator C so that the tines together constitute a generally horizontally disposed load

supporting means which may be lifted and lowered at the will of the operator by power supplied by the prime mover which is associated with the truck. As previously explained, the forks 15 are highly useful in the transportation of certain types of loads, without the application of a pallet, and are also well suited for engaging, lifting and transporting the conventional pallet.

The present invention contemplates the provision of a pallet generally indicated at S in the drawings, and which is preferably fabricated of metal and in plate form, relatively thin but substantially inflexible when loaded. It is rectangular and is provided at two adjacent corners with legs or supports, such as indicated at 16, solid legs being used if desired, but these supports preferably comprising castors. The nature of the supports is not important except that they should function to allow the forks to move under the floor of the pallet when the pallet rests with one end against the ground and with its other end raised by the supports. In Figure 11 the load carrying forks 15 of the truck are shown inserted under the platform, the end thereof not provided with permanent supports being mounted upon supporting blocks B so that the platform is substantially horizontal. This holding of the pallet floor horizontal is helpful in the loading thereof but is not essential. It is well to understand also that the supports 16 may be entirely eliminated and the pallet floor mounted on blocks thereby to permit entry thereunder of the truck forks.

Intermediate the castors 16, and welded or otherwise rigidly attached to the pallet, is an L-shaped catch 18 which projects downwardly (shown upside down in Fig. 8) and has a rearwardly projecting terminal end portion, this catch comprising one element of a means for separably connecting the pallet to the truck. The pallet is preferably not directly attached to any portion of the truck but to an intermediate means comprising two attachment members 20, one of which is shown in its entirety in Figure 4 of the drawings.

To those skilled in the art each member 20 will appear to resemble what is known as an extension fork, adapted to be slipped onto or off of a fork or tine 15 at will, and which, when positioned as shown in Figures 1 and 2, is locked to the tine. Actually, the functioning parts of members 20, to be set forth below, may be made integral with forks 15 and said attachments discarded. Locking and unlocking of members 20 to the forks is effected without the aid of tools or separate securing devices. Thus the flat plate which comprises the principal portion of member 20 is provided with downwardly projecting marginal flanges 20a and 20b which are adapted to engage the edges of the tine or fork 15 upon which the member is placed, to prevent the member from moving laterally. These flanges project beyond the end of the plate, and are provided with ears 20c which are connected by a cross bar 22. The space defined by this cross bar 22, the adjacent parallel end edge of the plate, and the flanges 20a and 20b is a tine receiving space, shown most clearly in Figure 9. Assembly of member 20 with element 15 is readily effected by inclining the member 20 as shown in Figures 9 and 10, advancing it axially of element 15 so that the free end of the element passes through the aperture provided for its reception, and thereafter moving member 20 longitudinally of element 15 until its leading end has been advanced as far as may be, whereupon it is lowered so as to lie di-

rectly upon the upper surface of the member 15 below it, the cross or locking bar 22 passing around, in such movement, the curved end of the tine 15 to a position in rear of the vertically extending continuation of this element, which is indicated at 15a in Figure 2. Attached flanges 20d abut, when member 20 is so positioned, against a portion 17b of the carriage so that this member is effectively locked against longitudinal movement. It is clear that, after assembly of member 20 with a supporting tine in the manner just described, this member cannot move unless by reversing the process of assembly, i. e. tilting it to the position shown in Figure 9 and sliding it outwardly along the tine and really is an integral part of the tine for all purposes.

Two such members 20 are preferably provided, and each, for at least a portion of its length, is substantially wider than the fork 15 upon which it rests, as clearly to be perceived in Figures 1, 3 and 4. These widened portions terminate, at the ends thereof which are provided with attachment means, in transversely extending edges 20e, which edges are in alignment when the two members are fully positioned as shown in Figure 1. These two edges or shoulders 20e together comprise one portion of the separable connection between pallet S and the truck, the other portion being the hook 18.

When the forks 15 and added members 20 are inserted beneath a loaded pallet S, and the pallet is lifted, the hook member 18 will not be caused, by such simple lifting movement, to actually engage the edges 20e. However, should there be any forward movement of the pallet upon the tines 15 as the truck is manipulated, the hook member will, after a short forward travel of the pallet, engage the edges 20e as seen in Fig. 7, thus preventing further travel of the pallet and its load off the fork lift. When a load is to be discharged and the pusher P is actuated while the truck is retracted the pallet S, if its hook 18 is still spaced from edges 20e, will of course slide forwardly with the moving load until the hook 18 engages edges 20e, further movement of the pallet upon its support being then prevented so that the pallet may be withdrawn with the forks from beneath the load which it has been supporting. Because of the fact that the hook 18 engages the undersides as well as the edges of members 20 the pallet is prevented also from tilting as the load passes over its forward edge, i. e. the edge thereof remote from the hook.

Disengagement of the pallet may be readily effected either by lowering the pallet to the ground and then slightly advancing the forks, further lowering and then retracting the fork lift, or by rearwardly tilting the mast and thus causing the pallet to slide toward the truck body. This last method of disengagement may be facilitated by moving the truck rearwardly and then suddenly bringing it to a stop, the inertia of the pallet S causing it to slide rearwardly until the hook has moved from beneath members 20. If desired, members 20 may be formed as illustrated in Figure 5, the catch portions 20e being retained but the forward portions of the members being of reduced width. Still other types of such attachment members may be employed, if desired. In any event the means for detachably securing the pallet to the truck must be so formed that the pallet will not only be restrained from sliding too far forwardly during an unloading operation but will also effectively prevent tilting of the pal-

let about the ends of the tines 15 during such operation.

The novel mechanism so far described may be utilized whether or not the truck is equipped with a pushing element such as illustrated in the drawings but is most useful when employed in association with a truck which is so equipped. The invention is of very great utility when employed in unloading the cargo of a railroad box car and in a case in which the cargo comprises granular or pulverulent material packaged in bags or in sacks, small boxes, or cartons, sacks of flour for instance, or cartons of canned goods. For the purpose of most conveniently unloading such a cargo from a box car, and storing it in a warehouse a truck and three pallets can be used with great economy as compared with unloading methods now commonly practiced.

In carrying out such unloading operation one of the load supporting pallets would be placed adjacent the door of the car to be unloaded, the two legs of this pallet resting directly upon the car bottom and the opposite end being supported upon blocks, for instance wooden blocks one of which is indicated at B in Figure 11, so that the pallet floor will be disposed horizontally. Actually, the pallet S could be merely a plate equipped with a hook 18 and supported entirely by blocks. The supports or legs are really important however to allow the forks to be disengaged from the hook 18 by the mere manipulation of the forks. Four men will then pile a predetermined number of sacks upon the pallet, such a pile of sacks being illustrated in Figure 11. This can be readily accomplished. The lift truck would then advance, the fork lift platform F inserted under the pallet, as illustrated in Figure 11, and the carriage C elevated so that the fork lift with its superposed load will be lifted. The truck will then be operated to transport the load to the storage area. At the point of load discharge the operator will cause the mast of the truck to tilt forwardly to a position such as that in which it is illustrated in Figure 12, the carriage and fork lift platform likewise being tilted forward as shown. If the load is to be deposited directly upon the floor the tilting operation will bring the forward edge of the pallet S into contact with the floor, the carriage C occupying such position that tilting to an angle of 2° or 3° or thereabouts will have this result. The operator would then cause the carriage C to move upwardly for the fraction of an inch, for instance about a quarter of an inch, thus causing the forward edge of the pallet to be elevated above the floor that amount.

The hydraulic mechanism H is then energized to cause the pusher frame P to move forwardly and, simultaneously, the truck is backed away. The pallet S is thus withdrawn from beneath the pile of sacks which are held against lateral movement by the pusher element P. As the pallet S is withdrawn from beneath the sacks comprising the pile, these sacks pass over the forward beveled edge of the pallet and drop to the floor. The drop is so slight, however, that there is no breakage of any sack as it passes over the edge of the pallet and there is, furthermore, no such relative movement between the sacks as to cause the pile to lose formation. The entire pile will be delivered intact and in tight pile formation upon the selected space, without possibility of breakage or disruption of any sack.

Should one load already have been deposited on this selected storage area as in Fig. 12, and it be desired to deposit a second load on top of

the first, the procedure will be the same except in that the pallet S and the load carried thereby will be elevated by moving the supporting carriage C upwardly, for instance to the position shown in Figures 12 and 13. The unloading operations will take place, however, just as before, the truck being backed away while the pusher operating mechanism is actuated in such manner as to hold the load stationary. If desired a third load may be deposited in this manner upon the top of the second and the resulting pile will be stable, the individual increments deposited having been maintained in tight pile formation because each was made to drop an extremely inconsequential distance.

After each load is deposited the lift truck will return to the box car, the pallet being preferably released while the truck is on this return movement, the operator tilting the mast backwardly so that the pallet slides toward the truck until the hook 18 disengages the catch members 20e. When the truck arrives at the loading station therefore, the pallet may be readily deposited upon the floor by simply lowering the carriage C until the pallet makes contact with the floor, the fork lift being then retracted as legs or supports 16 hold the pallet so as to allow the retraction of the truck forks. When such legs are not used, one or more hooks 18 may function as legs for the same purpose, as well as engaging members. Also, where other engaging means are used, it may be desired to remove the pallet manually and legs may be dispensed with, the pallet being entirely supported by blocks to allow the forks to enter thereunder. The truck will then be moved to pick up a pallet which has previously been loaded and will carry this loaded pallet to the discharge area and effect the discharge of the sacks therefrom in the manner previously described. The sacks are piled one upon another and the use of conventional pallets is wholly avoided. Not only is there a substantial saving realized by reason of the fact that the use of conventional pallets is avoided but there is also realized a substantial saving in labor even though as many men are required in an unloading operation effected by means of a truck equipped with the novel mechanism described as are customarily used when the unloading operation is effected by means of the conventional pallet. It is actually found that the labor costs may be reduced by about 15%, in the unloading of a car containing a specified number of sacks, this saving in labor being due to the fact that the truck is called upon to handle only three pallets instead of a large number of pallets, say 40 pallets in the case of a car of normal capacity.

When flour in sacks is to be loaded into a box car, instead of being removed therefrom, much greater economies are realized as compared with known methods. Thus, in such a reloading operation effected with the aid of the improved mechanism described, only two men will be required as the lift truck can place the pallet where it is wanted without handling. The pallets are loaded within the warehouse or mill and the lift truck transports a load to the car and deposits it in the car, successive loads being placed one upon the other by the truck to the limit permitted by the height of the roof, without, as previously explained, any handling. In determining the number of bags to be incorporated into each successive load consideration must be given to the distance the machine travels from the point of loading of the pallet to the point of discharge of

the load in the box car, the loads being preferably so made up that the men loading the pallets can always be ahead of the truck. This permits the truck to travel continuously at its maximum speed so that the most economical results are, in this respect, realized. Two men can, without undue exertion, load pallets slightly faster than the truck can remove them, the operation being so planned and, toward the end of the loading may have loaded several skids or platforms in excess of the number withdrawn by the truck. The men who have thus been actually loading the pallets within the warehouse may then move to the car and assist in the manual storage within the car of that portion of its loading which must be stacked by hand, i. e. the area adjacent the door of the car. When three men are thus used to load a car the saving of labor, as compared with the situation in which conventional pallets are used and involving the employment of five men, is approximately 40% and, in addition, there are no empty pallets to handle so that the saving can and frequently does amount to 50% over present methods employing conventional pallets. On the complete operation of unloading, storing and reloading a box car there may thus be an overall labor saving over present methods, of 25% to 30% of the total actual labor costs and this is in addition to the additional saving realized by dispensing with the use of a large number of pallets.

Having thus described the invention, what is claimed as new and desired to be secured by Letters Patent is:

1. A load carrying pallet for a fork lift truck, adapted to be loaded, picked up and transported, said pallet comprising a rigid plate having means affixed thereto for supporting one edge only so that the pallet, when placed upon a horizontal support, will be inclined, and a hook attached to the underside of the pallet adjacent the edge so elevated and extending downwardly and inwardly, for the purpose set forth.

2. A load carrying pallet for a fork lift truck, adapted to be loaded, picked up and transported, said pallet comprising a rigid plate, and a hook attached to the underside of the plate extending downwardly and inwardly, for the purpose set forth.

3. In a combination of the class described, a lift truck having a lifting platform with a detent-lift truck having a lifting platform with a detent-engaging surface, said platform being adapted to

carry a load by application under the load, a thin sheet-like pallet adapted to be lifted by said lifting platform, locking means extending downwardly from said pallet and coacting with said detent-engaging surface for locking said pallet against substantial sliding relatively to said lifting platform when resting in a predetermined position on said platform, said locking means including a portion for locking said pallet against tilting upwardly off said lifting platform as when said pallet extends unsupported forwardly beyond said lifting platform and a load is applied to said forwardly extending portion.

4. In a combination of the class described, a lift truck having a lifting platform adapted to carry a load by application under the load and having a detent-engaging surface, a thin sheet-like pallet adapted to be lifted by said lifting platform, means extending downwardly from said pallet and coacting with said detent-engaging surface for locking said pallet against substantial sliding relatively to said lifting platform when resting in a predetermined position on said platform, said means including a portion for locking said pallet against tilting upwardly off said lifting platform as when said pallet extends unsupported forwardly beyond said lifting platform and a load is applied to said forwardly extending portion, and said means being so positioned relatively to said pallet as to maintain said pallet with one edge against the ground and the floor of the pallet angular to the ground when the pallet rests on a flat piece of ground.
